UNITED STATES PATENT OFFICE.

AUGUST HEINE, OF SILVER CREEK, NEW YORK.

CENTRIFUGAL FLOUR-BOLT.

SPECIFICATION forming part of Letters Patent No. 309,716, dated December 23, 1884.

Application filed April 17, 1884. (No model.)

To all whom it may concern:

Be it known that I, AUGUST HEINE, of Silver Creek, in the county of Chautauqua and State of New York, have invented new and useful 5 Improvements in Centrifugal Flour-Bolts, of which the following is a specification.

This invention relates to an improvement in that class of flour-bolts in which a rotating bolting-reel and rotating beaters within the 10 reel are employed.

The object of my invention is to so construct the reel that the inner side of the bolting-surface shall be as little obstructed as possible, and to reduce the disintegrating action of the 15 reel, and to provide simple and efficient means for keeping the meshes of the bolting-cloth clear.

My invention consists of the improvements in the construction of the reel, which will be 20 hereinafter fully explained, and pointed out in the claims.

In the accompanying drawings, Figure 1 is a vertical cross section of a bolting-reel provided with my improvements. Fig. 2 is a perspective view of the devices whereby the bolting-cloth is supported. Fig. 3 is a fragmentary longitudinal sectional elevation of the same parts. Fig. 4 is a fragmentary longitudinal elevation of the device for clearing the 25 meshes of the bolting-cloth. Fig. 5 is a cross-section, on an enlarged scale, of the clearing device.

Like letters of reference denote like parts in the several figures.

35 A represents the stationary frame, and a the inclosing-casing of the reel, attached thereto. B represents the bolting-reel arranged in the casing a, and provided with well-known devices whereby it is rotated in the direction 40 of the arrow, Fig. 1.

c represents the horizontal beater-shaft, arranged axially in the reel B; and C represents the beaters, secured to spiders c', mounted on the shaft c. The shaft c and beaters C are rotated in the same direction as the reel B, but 45 at a greater speed, in the usual manner.

D represents one of the heads or end disks of the reel. All of these parts may be of any ordinary and well-known construction.

50 E represents the longitudinal ribs, which

are secured with their ends to the heads D at the end of the reel, near the periphery thereof, in a well-known manner. The ribs E are made inclined on their outer sides, so as to present their narrow edges to the material escaping from the beaters, whereby the material, which is driven by the beaters against the ribs E, is deflected outwardly toward the bolting-cloth. At the same time the quantity of material which comes in contact with the 55 ribs is greatly reduced by the tapering cross-section of the same, thereby reducing the disintegration of material by being thrown against the ribs.

The inner sides of the ribs E are arranged 60 tangential to a circle drawn concentric with the axis of rotation of the beaters, so as not to deflect any of the material inwardly or away from the bolting-cloth.

F represents standards secured to the outer 70 sides of the ribs E, and G are rings, which are secured to the outer ends of the standards F, to support the bolting-cloth H, which is stretched over the rings G. The latter are secured to the standards, and the standards to the ribs 75 E by bolts i, which pass through these parts, as clearly represented in Figs. 1 and 3. The standards F are provided with base-pieces f, fitting against the outer inclined sides of the ribs, and having end flanges, f'', bearing against 80 the edges of the ribs, whereby the standards are firmly supported on the ribs. The standards F support the rings G and bolting-cloth H at such a distance from the outer sides of the ribs E that the space between the ribs and 85 the bolting-cloth is not liable to become obstructed by accumulated material, thereby retaining the entire inner side of the bolting-surface in a free and unobstructed condition.

k represents the rotating clearer-shaft, arranged within the casing a, outside of the reel and parallel therewith.

v represents light balls, attached to the shaft k by strings, straps, or flexible connections m, of such length that the balls will impinge against 95 the bolting-cloth in rotating with the shaft k and jar the cloth with sufficient force to dislodge any material which may adhere to the same. The balls l are preferably made of rubber and hollow, and attached to the strings m by swiv- 100

eling-connections N. The latter are composed of balls n, adapted to be passed through openings in the rubber balls l and wire eyes n', to the stems of which the balls n are secured, as 5 represented in Fig. 5. The rubber balls are free to turn on the stems of the wire eyes n'. The rotation of the shaft k causes the balls to impinge against the bolting-cloth and to rebound therefrom immediately after the blow 10 is delivered, whereby the cloth is subjected to a succession of light blows, which jar the cloth and dislodge the material from the meshes without wiping the cloth, which would tend to further rub the material into the meshes of 15 the cloth and wear the latter rapidly.

I am aware that a revolving shaft provided with beater-cords is not new, and that a stationary shaft provided with flexibly-connected balls and combined with a polygonal reel 20 is not new, and I do not claim either of these constructions.

I claim as my invention—

1. In a bolting-reel, the combination, with beaters revolving within the reel, of longitudinal ribs E, constructed with inclined outer 25

sides, which deflect the material discharged by the beaters toward the bolting-cloth, and inner tangential sides, which do not deflect the material, substantially as set forth.

2. In a bolting-reel, the combination, with 30 beaters revolving within the reel, of longitudinal ribs E, made tapering in cross-section, and arranged to present their narrow edge to the material which is discharged by the beaters, substantially as set forth.

3. The combination, with a revolving bolting-reel, of a rotating clearer-shaft, k, provided with balls l, attached to the shaft by flexible connections, substantially as set forth.

4. The combination, with the rotating clearer-shaft k, of hollow balls l, strings or straps m, secured to the shaft, and swiveling connections N, whereby the balls are attached to the strings or straps, substantially as set forth.

Witness my hand this 11th day of April, 45 1884.

AUG. HEINE.
